RINGING CODE DETECTOR

Glenn L. Richards, Ames, Iowa, assignor to General Dynamics Corporation, Rochester, N.Y., a corporation of Delaware

Application December 14, 1956, Serial No. 628,394

2 Claims. (Cl. 179—17)

This invention relates to telecommunication systems and particularly to code ringing arrangements for party line telephone systems.

The object of the invention is to provide substation means which will respond to code ringing potentials applied to a substation line and render effective only the particular code to which the particular substation is arranged to respond.

As a specific example of code ringing arrangements, attention is directed to the copending application of George Elliott, Serial Number 432,755, filed May 27, 1954. Here is provided a means whereby a plurality of substations are connected to a line and arrangements are made to call these stations by one ring and two ring codes. It therefore appears that the substations will be grouped in pairs and both substations of each pair will respond to the same ringing current, it being left to the subscribers to mentally differentiate between the one ring and two ring codes. It is desirable, however, to sound the substation bell only when the party thereat is wanted. The object of the present invention is to provide a circuit means at each substation which will pass only that code to which the particular substation is intended to respond.

The invention resides in a pair of electronic circuits, a first of which will respond to a two ring code and will exclude a one ring code and a second of which will admit a one ring code and will exclude a two ring code. This arrangement is possible due to the fact that standard and conventional arrangements are such that the two rings of a two ring code are each much shorter than the one ring of a one ring code. It will be noted, in the Elliott arrangement, that the total ringing time of each code is the same, it being continuous in the case of the one long ring code and being divided and spaced apart in two equal intervals in the case of the two short ring code.

In accordance with the means provided to pass a long ring but exclude a two ring code, an electronic circuit having a timing means for reaching a given stage of operation in a period just over the length of one ring of a two ring code is provided and controlled by a fast acting relaxation circuit whereby the operation of this timing means will have to be started from the beginning at the beginning of the second ring of the two ring code with the result that a two ring code cannot pass into the ringing circuit. However, if a one long ring is received, the said timing circuit will operate and will pass the ringing current into the ringing circuit for the last half of the code. The particular station, arranged to respond to the one long ring code will therefore be rung although the actual length of the ring will not be as long as that provided by the ringing arrangements.

In accordance with the means provided to pass a two ring code but to exclude a one long ring code, means is provided to immediately respond to the beginning of a ring either a short ring of a two ring code or a long ring of a one ring code and to establish an excluding condition to exclude the ringing current from the bell circuit

as long as this ring is maintained, thus preventing any ringer response to a long ring code and to the first ring of a two ring code. The circuit is, however, provided with a slow acting relaxation circuit which will practically maintain an established condition which will allow the ringing current to enter the ringing circuit at the beginning of the second ring of the two ring code. Therefore only the second ring of the two ring code will operate the station ringer and the effect there will be exactly the same as at those stations where the one ring code is effective, that is, a standard ringing pattern is provided so that each station will be rung in a standard manner as though it were on a single party line.

The slow relaxation circuit embodied in this circuit to pass the two ring code consists of a gas trigger tube having a starting anode connected in a circuit which will initially respond to excitation by presenting a potential above that required to fire the tube but where the potential of this starting anode will shortly fall below such point and where this lowered potential will be maintained for a substantial period even after the excitation has been removed so that when excited by a second ring, the tube which is quenched between rings cannot be triggered a second time. This immediately operated tube is employed to place a load on a voltage divider circuit leading to the starting anode of the main ringing current passing tube so that this last tube is prevented from operating during the first ring of a two ring code or during the whole of a one long ring code. However, when the first ring of a two ring code comes to an end, this load will be relaxed as the first of these tubes ceases to conduct. The potential of the starting anode of this first tube, however, is maintained at a value below the critical value of this tube so that when ringing current is again transmitted into the circuit this first tube is prevented from firing and since it can no longer impose a load on the said voltage divider circuit, the potential of the starting anode of the second tube will rise above its critical value and this last tube will thereupon conduct ringing current to the substation ringer.

A feature of the invention is the use of two types of substation pad circuits, one for use at a substation ranged to be signalled by a single long ring code and other to be signalled by a two short ring code which will only respond to such codes and will translate such code to a uniform single ring code. Each pad will respond to a particular code and each will exclude all other codes but will produce a standard output, the same at all stations. While the one ring signal thus produced is about the same length as one ring of a two ring code, it is still adequate for substation signalling and it has the virtue of being the same at all stations and being effective at only that station intended to respond to a particular code. Thus each subscriber will only be called when actually wanted.

Another feature of the invention is a circuit means requiring a double application of current thereto for rendering means, to pass such current to a use circuit, effective, in which a first application of current is employed to block said means and to establish a condition which will persist over a period constituting a silent period of the code and which established condition will, on a second application of current, render said blocking means ineffective.

Another feature of the invention is the use of a trigger tube for loading the circuit of a relay means to prevent the operation thereof and the use of a trigger potential circuit for said trigger tube having a time constant that its initial high potential surge is reduced to a value below a critical value and maintained at such a value over a period of no excitation for a predetermined length of time. This trigger tube has a starting

circuit which will respond to an initial energization to produce a potential above a critical value but which will quickly fall below such critical value and then block any attempt to raise it above such critical value for a predetermined time whereby such trigger tube rendered non-conducting cannot be triggered into operation again within a such predetermined time.

Another feature of the invention is an electronic circuit acting within its first two steps as a scale of two device whereby it requires a succession of at least two energizing intervals to reach a desired state. By such means a circuit may be constructed and arranged to respond to a two ring code on a telephone line and to reject any one ring code.

Other features will appear hereinafter.

The drawings consist of three sheets having six figures, as follows:

Fig. 1 is a schematic circuit diagram of a two ring pad for excluding all one ring codes and for passing a ringing signal triggered by a two ring code to the substation where it is located, the pad being shown connected to one of the line wires and arranged to respond to ringing current superimposed on a positively biased current;

Fig. 2 is the same circuit but arranged to respond to ringing current superimposed on a negatively biased current;

Fig. 3 is a schematic circuit diagram of a one ring pad for excluding all two ring codes and for passing a ringing signal triggered by a one long ring code to the substation where it is located, the pad being shown connected to one of the line wires and arranged to respond to ringing current superimposed on a positively biased current;

Fig. 4 is the same circuit as that of Fig. 3 arranged to respond to ringing current superimposed on a negatively biased current;

Fig. 5 is a set of graphs plotted against time to show the two ring code input, the response of the two ring pad, the response of the one ring pad and the output ringing signals at the substation provided with the two pad; and

Fig. 6 is a similar set of graphs plotted against time to show the one long ring code input, the response of the two ring pad, the response of the one long ring pad and the output ringing signals at the substation provided with the one long ring pad.

Looking at Fig. 1 it will be noted that to the line which may be either the tip or ring of a telephone at the substation, there is connected a two ring detector 2 through a triggered tube V-2 to ground so that ringing current flowing over the line will operate the detector to attract the attention of the subscriber thereto. The circuit of Fig. 1 is arranged to respond to ringing current superimposed only on a positively biased current, the anode of the tube V-2 must be positively biased. If the ringing current is superimposed on a negatively biased current, then the pad must be connected as shown in Fig. 2 where the anode of the tube V-2 will be positive with respect to its cathode.

After the tube V-1 is fired and as the condensers C-2 and C-3 attain their charge, the potential at the junction of resistances R3 and R4 is lowered to a point considerably below the potential required for firing the tube V-1, this tube having been fired nevertheless remains in conducting state and this condition will continue as long as ringing current is transmitted over line 1.

The two ring pad of Figs. 1 and 2 is constructed and arranged to enable the ringer 2 only in response to a two ring code and to prevent the enabling of the ringer in response to a one long ring code. The outstanding feature of the operation of this circuit is that a first tube V-1 is immediately fired before the con-

densers C-2 and C-3 can have been charged and by the conduction of current from its main anode to its cathode will depress the potential at the junction of resistances R-5 and R-6 and likewise depress the potential at the junction of the resistances R-6 and R-7 below the firing potential of the tube V-3. As long as the ringing current is supplied to this circuit, then, the tube V-3 will be prevented from firing and thus the circuit will not respond to a one long ring code. However, at the end of any ring which caused the firing of the tube V-1, the charge on the condensers C-2 and C-3 will begin to dissipate. If now the silent interval is short as between the two rings of a two ring code, these two condensers do not become fully discharged and the following application of ringing current will not produce a surge to provide a firing potential to the starting anode of the tube V-1 and hence this tube fails to fire and consequently the full potential of the network is applied across the voltage divider consisting of the resistances R-5, R-6 and R-7 and consequently the potential at the starting anode of the tube V-2 rises sufficiently for this tube to fire. Since the continuation of the ringing current merely drives the condensers C-2 and C-3 to full charge, the tube V-1 will not fire and the tube V-2 will remain active.

In somewhat more detail the circuit of Fig. 1 operates in this manner. The diode 3 isolates the circuit from the talking conductor 1, and the V-2 tube while inactive performs the same function during the talking period. When ringing current appears on the line 1, this being of higher potential, it passes through the diode 3, the R-1 resistance and the condenser C-1. The variable resistance R-1 is used to compensate for the effect of line loss and is not reset after its initial adjustment on a particular installation. The two condensers C-1 and C-2 and the two rectifier diodes 4 and 5 constitute a voltage doubling direct current power supply. The NE2 neon diode is used as a voltage regulator and the R2 resistance limits the peak currents through the voltage regulator.

The C-2 condenser charges up in relatively short time after the ringing current appears on the line 1. The C-3 condenser couples this large and rapid voltage change to the starting anode of V-1 and then as it starts charging brings the potential of the starting anode down toward the proportion of the supply voltage determined by the voltage divider circuit R-3 and R-4. As a result of the initial voltage surge on the starting anode, the starting anode to cathode gap breaks down and the tube V-1 then fires through the resistance R-5. With the main anode of the tube V-1 conducting, the potential at the junction of the resistances R-6 and R-7 is too low to trigger the tube V-2.

The above described action takes place every time that ringing current is transmitted over the line whether the bias is positive or negative. If the detector is attached for positive bias, as shown in Fig. 1, and negative bias is connected to the line, V-2 will not conduct no matter what ringing code is applied. Likewise, a detector connected for negative bias as shown in Fig. 2 cannot conduct ringing current with positive bias applied because of the characteristics of the gas relay tube V-2.

The detector of Figs. 1 and 2 is meant to allow the ringer in the subscriber's telephone set to ring when the code is a two short ring code. The operation is depicted in Fig. 5 where the two short ringing intervals are shown as covering the periods t_1 to t_2 and t_3 to t_4 . The graphs in the bracket marked 2 ring pad show the potentials at the starting anodes of the tubes V-1 and V-2. The condenser C-1 charges up very shortly after time t_1 and since the tube V-1 immediately fires the potential on the starting anode of tube V-2 is held below the value necessary for the firing of this tube. At time t_2 the condenser C-2 begins to discharge through the high

resistance bridge R-3 and R-4 and the condenser C-3 likewise begins to discharge through R-3. However, the time constant is such that the potential at the starting anode of the tube V-1 is held at a value below the firing point of this tube whereby when ringing current is again applied to the line at time t_3 , V-1 is prevented from firing and there now being no load on the resistance R-5, the potential at the starting anode of V-2 rises beyond the critical value. Therefore during the interval between time t_3 and t_4 the tube V-2 will conduct ringing current through the ringer 2.

When the code is the one long ring, the action is depicted in Fig. 6. Here the tube V-1 is immediately fired and since there is a load on the resistance R-5 the potential of the starting anode of V-2 remains constantly below the critical value from time t_2 to time t_4 and the tube V-2 does not fire.

The long time constant of this circuit is shown by the slow decay of the potential of the starting anode of V-2 between times t_2 and t_3 and between times t_4 and the next t_1 in Fig. 5 and between times t_4 and the next t_2 in Fig. 6. It will be understood that these graphs have been idealized to bring out clearly the operation of the circuits of the present invention.

In both Figs. 5 and 6, certain areas have been filled in during the time that ringing current is applied to the line and during which the tube V-2 (in Figs. 1 and 2) and tube V-3 (in Figs. 3 and 4) are made to conduct. The lowermost graph in both Figs. 5 and 6, marked output, represent the application of ringing current to the ringer 2. It will be noted that the 2 ring pad (of Figs. 1 and 2) and the one long ring pad (of Figs. 3 and 4) both produce an output consisting of one short ring between times t_3 and t_4 and since these are produced at different substations on the same party line it will simulate the operation of a single party line and no subscriber will be annoyed by having to listen to codes used to summon other parties on the line.

The operation of the one ring pad of Figs. 3 and 4 is somewhat different since there is no intermediate tube to fire immediately to hold the potential of the fired tube down. The time constant of this circuit differs as shown in Figs. 5 and 6, in that the build up of the potential on the starting anode of the tube V-3 is slow and will not reach the critical value within the limits of one of the short rings. Therefore as shown in Fig. 5 in the graph marked "1 ring pad," the potential of the starting anode of V-3 rises slowly during the first ring of a two ring code and reaches a critical value just beyond the time t_2 and then drops quickly so that at time t_3 the action starts over from the beginning. Thus the 1 ring pad (of Figs. 3 and 4) will pass no ringing current on a two ring code. However, when a long ring is applied to the line as depicted in Fig. 6, the potential of the starting anode of V-3 will reach the critical value shortly after time t_3 so that ringing current will be applied to the ringer 2 for the remainder of the one long ring.

By this means each substation of a party line may be provided with an electronic circuit powered entirely by current transmitted over the line and will convert the coded ringing current to a different code to simulate the operation of a single party line.

The value of the various components marked on the drawings and the commercial designations used are by

way of example and are used merely to give a clear understanding of the spirit of the invention.

What is claimed is:

- 5 1. In a telephone system, a subscriber line having a plurality of substations thereon and each substation having a ringer, means for selectively signaling said substations consisting of means for applying coded ringing current thereto including codes of two short rings and codes of one long ring, an electronic circuit at each said station intended to be signaled by a two short ring code, said circuit having two electronic tubes and being responsive to ringing current transmitted thereto over said subscriber line for rendering a final one of said tubes conducting in response to a second application of said ringing current thereto closely following a first application of said ringing current thereto and for preventing the enablement of said final tube in response to a single application of said ringing current thereto, said circuit including a first tube having means to block the enablement of said final tube, a triggering circuit for said first tube consisting of a voltage divider, a mid tap therefor constituting a triggering conductor and a condenser bridged about one half said voltage divider and acting when uncharged to communicate the potential applied to said voltage divider to said triggering conductor and when charged to communicate the potential of said mid tap to said triggering conductor, and a circuit for said ringer controlled by said final tube.
- 10 2. In a telephone system, a subscriber line having a plurality of substations thereon and each said substation having a ringer, means for selectively signaling said substations consisting of means for applying coded ringing current thereto including codes of two short rings and codes of one long ring, an electronic circuit at each said substation intended to be signaled by a two short ring code, said circuit having two electronic tubes and being responsive to ringing current transmitted thereto over said line for rendering a final one of said tubes conducting in response to a second application of said ringing current thereto, closely following a first application of said ringing current thereto and for preventing the enablement of said final tube in response to a single application of said ringing current thereto, said circuit including a rectifying means for deriving a direct current from said ringing current, a voltage divider circuit having a high potential portion and a low potential portion connected to said direct current source, a mid tap from said voltage divider, a condenser bridged across the high potential portion of said voltage divider circuit, a first tube for controlling said final tube and a triggering circuit for said first tube controlled by said mid tap connection, and a circuit for said ringer controlled by said final tube.
